UNITED STATES PATENT OFFICE.

REINHARD HILDEBRAND, OF WEBSTER GROVES, MISSOURI.

CYLINDER-HEAD FOR INTERNAL-COMBUSTION ENGINES.

1,376,621.

Specification of Letters Patent.

Patented May 3, 1921.

Application filed December 4, 1919. Serial No. 342,372.

To all whom it may concern:

Be it known that I, REINHARD HILDEBRAND, a citizen of Germany, a resident of Webster Groves, in the county of St. Louis 5 and State of Missouri, have invented certain new and useful Improvements in Cylinder-Heads for Internal-Combustion Engines, of which the following is a full, clear, and exact description, reference being had 10 to the accompanying drawings, forming a part of this specification.

This invention relates to improvements in cylinder heads for internal combustion engines, the invention being especially 15 adapted for use in very large internal combustion engines of the Diesel type, wherein the ignition is effected by compressing air to about 500 lbs. pressure per square inch, thereby producing a temperature of about 20 1000° F. The temperatures resulting from combustion usually range from about 2000° F. to 2500° F. Actual experience has shown that comparatively small Diesel engines of less than a few hundred horse-power, 25 can be carefully designed to withstand the stresses resulting from high pressures and high temperatures, and it may appear that much larger engines could likewise be readily designed by merely copying 30 the smaller designs, but this is not true. In fact, the very large Diesel engines have never been entirely successful. Their cylinder heads have not withstood severe stresses resulting from the intense heat and high 35 pressure in the combustion chambers, this being especially true of engines having cylinders larger than 26 to 30 inches in diameter. As a consequence, very large engines of the Diesel type, although highly 40 economical so far as fuel is concerned, have not come into general use.

The cylinder heads of small engines form the top walls of comparatively small combustion chambers, and by cooling these 45 small heads injurious stresses can be avoided, but in a much larger engine, the combustion space is very large in comparison with the cooling surfaces at the walls of the combustion chamber, and owing to the increase in volume of the fuel without a corresponding increase in cooling area, the 50 walls of the large combustion chambers are subjected to comparatively high temperatures. Furthermore, the large combustion

chamber is relatively high and very intense 55 heat is generated at the center of the combustion chamber, as well as at the center of the cylinder head forming the top wall thereof.

Owing to the extremely high temperatures 60 at the central portions of large cylinder heads, and the lack of opportunity for proper cooling, the cylinder heads of large Diesel engines eventually crack near the center. Heat variations cause expansion 65 and contraction of the cylinder head, which is a complex casting containing valves and subjected to high pressures, and great difficulty has therefore been experienced in designing large cylinder heads capable of 70 withstanding even a brief period of service. The difficulties of this problem are fully appreciated by engineers familiar with Diesel engines, and the failure to produce very 75 large engines of this type adapted to stand the heat and pressure without breakage in the cylinder heads clearly shows that there must be some unusual difficulties preventing a solution of this particular problem. I will, therefore, briefly point out conditions 80 existing in cylinder heads of this kind, and endeavor to show why the stresses do not result in breakage of my cylinder head.

The ordinary type of cylinder head has a central portion opposing the engine piston 85 and exposed directly to the high pressures and intense heat resulting from combustion in the cylinder. This highly heated central portion is usually surrounded by a water-cooled marginal portion seated upon the 90 top of the cylinder. Obviously, the water-cooled margin tends to prevent expansion of the central portion, but the fire-heated central portion must expand, and as a result the large cylinder heads eventually crack 95 near the center, as will be hereafter pointed out. My object is to eliminate stresses which have heretofore resulted in fractures in large cylinder heads.

Figure I is a horizontal section on the 100 line I—I, Fig. II, showing a cylinder head embodying the features of this invention, a portion of the head being broken away.

Fig. II is a section on the line II—II, Fig. I, showing the cylinder head applied 105 to a cylinder.

Fig. III is a section taken approximately on the line III—III, Fig. I.

Fig. IV is a diagrammatical view showing the heat-exposed face of the cylinder head.

Fig. V is a diagrammatical vertical section, showing a slightly different head applied to a cylinder.

1 designates the cylinder of an internal combustion engine, and 2 designates a piston adapted to reciprocate in the cylinder. To illustrate one form of the invention, I have shown a hollow cylinder head in the form of a single casting having a bottom wall E, side walls 3 and a top wall 4, all integrally connected together. Ports 5 are formed in the side walls 3 for the admission and discharge of cooling fluid, preferably water, which passes through the hollow cylinder head as suggested by arrows in Fig. II. The bottom of the cylinder head is larger than the internal diameter of the cylinder, and the marginal edges of this bottom are seated upon the top face of the cylinder. Vertical bolts 6 detachably secure the cylinder head to the cylinder.

25 The Diesel engine head shown in Figs. I to IV is provided with the usual inlet port 7 for the admission of air, exhaust port 8 for the discharge of products of combustion, and injector 9 whereby fuel is injected into the combustion chamber. To receive the injecting device an opening is formed in the center of the bottom wall E, at a point directly between the inlet and exhaust ports, which are preferably formed in said bottom wall. A tube 9' surrounds the fuel injecting device, said tube being secured as shown in Fig. II.

The bottom wall E of the cylinder head has central portions exposed directly to the heat of the combustion chamber and marginal portions seated upon the top of the cylinder. A cavity, or recess, R formed in the heat-exposed portion of the cylinder head, is provided with a top wall 10 and relatively narrow side walls 11 whereby said top wall is integrally connected to the bottom wall E. The inlet and exhaust ports are preferably formed in the wall 10 of the recess R, said recess forming part of the combustion chamber.

Theory and actual experience show that the ordinary large cylinder head cracks in the direction A—B (Fig. IV), this being the typical "Diesel head crack." It is generally termed a "heat crack," for the stresses due to heat greatly exceed those due to pressure. While the engine is running, both of these stresses vary constantly, fluctuating in wide limits. After each ignition follows a rapid rise in temperature and consequently an increase in stress up to a maximum. Then follows a decrease, down to minimum until the compression stroke begins, when the temperature and consequently the stresses begin to increase. The fibers of the metal,

therefore, are continually elongating and contracting, and if the fibers thus affected are not permitted to yield freely, they will eventually fail as a result of "fatigue," which produces the typical "Diesel head crack."

The ordinary Diesel head is a hollow casting having a flat bottom wall with central portions exposed directly to the heat generated in the combustion chamber, and these heat-exposed portions are surrounded by relatively cool marginal portions not directly exposed to the burning fuel. The marginal portions of the ordinary head are not only protected from direct action of the fire, but they are also cooled by water circulating through the cylinder head. It is obvious that the central portions of the cylinder head bottom, being exposed directly to the fire, must expand, and if such expansion is effectively resisted, or prevented, destructive stresses are bound to occur. In a cylinder head having water-cooled margins protected from direct action of the fire, these relatively cool margins may be compared to a non-yielding collar shrunk onto the heat-exposed central portions, and if the cylinder head bottom is in the form of a flat plate, its margins will very effectively oppose expansion of the central portions. The heat-exposed central portions of a perfectly flat plate cannot freely expand if they are surrounded by an integral non-expanding marginal portion.

Some advantage may be gained by making the cylinder head only slightly larger than the internal diameter of the cylinder, but this alone would not eliminate the destructive stresses due to a comparatively cool or "non-expanding" marginal portion.

Since the ordinary cylinder heads crack in the direction A—B (Fig. IV) and not in the direction C—D, it is evident that the stresses in the direction C—D are greater than in the direction A—B, for a rupture due to tensile or compression stresses is always approximately at a right angle to the stress. In the ordinary head, with a comparatively "non-expanding" margin, it appears that expansion in the direction C—D is very firmly opposed by the resistance at the margin, while in the direction A—B some expansion is permitted at the inlet and exhaust ports. The metal at these ports is yielding not only because the walls of the ports can be forced to a slightly oval form, but primarily because it is cooled at these points, and thus contracted, by the comparatively cool exhaust gases passing through one port and by the cold air passing through the other. I, therefore, believe it is especially desirable to relieve the stresses in the direction C—D.

Attention is now directed to the diagrammatical views (Figs. IV and V) which show that the recess R is elongated in the direction A—B. Some expansion in this direc-

tion is permitted by physical displacement of the metal forming the ports, and by the cooling action of the incoming and outgoing fluids tending to cause contraction of the metal forming the walls of the ports. However, we are faced with the problem of preventing destructive stresses in the direction C—D. The central portions of the bottom wall E are exposed directly to the heat resulting from combustion, and since these central portions are more intensely heated than the marginal portions, I permit differential expansion which could not occur in the ordinary cylinder head having a flat bottom wall.

The new cylinder head, instead of having a flat and rigid bottom wall, is comparatively flexible, the wall element 10 at the top of recess R being capable of expanding relative to the marginal portions of the head. This comparative flexibility is obtained by the action at the side wall elements 11 whereby the elongated heat exposed wall element 10 is integrally connected to the cylinder head. Since wall elements 11 lie at an angle to the elements with which they are integrally connected, said elements 11 are comparatively free to yield without fracture, when the heat exposed wall 10 expands relative to the outer portions of the cylinder head. For these reasons, the elements 11 may be termed yieldable connections. They are integrally connected to other portions of the head, and they provide sufficient flexibility to permit the desired differential expansion without fracture.

The central portions of the combustion chamber are hotter than the margins thereof, and the central portions of the heat-exposed face of the cylinder head are likewise hotter than the portions remote from the center. So the wall element 10, directly exposed to the heat at the center line of the combustion chamber, will expand and contract relative to the cooler outer portions, and the yieldable elements 11 will permit such expansion and contraction, thereby eliminating destructive stresses which have heretofore caused the typical "Diesel head cracks."

When compared with a flat plate, the heat exposed wall E has the advantage of yieldingness which permits differential expansion of the elements exposed to different temperatures, and this recessed wall is also stronger than a plain flat wall.

The wall E may be cooled in any suitable manner, but its top face is preferably exposed directly to the cooling medium, while the bottom face is exposed directly to the heat generated in the combustion chamber. The recess R may be of any suitable shape, and the inlet and exhaust ports may be formed in any suitable parts of the engine. However, I prefer to follow the general prac-

tice of forming the ports in the bottom wall of the cylinder head, as shown in the drawings, and it is therefore an advantage to form the elongated recess as herein shown, so as to eliminate destructive stresses in the direction C—D. A further advantage of the elongated recess lies in the fact that its elongated wall elements 11 will yield more freely than a circular wall. A very important feature of the invention lies in the "yieldable connection," between the central and marginal portions of the heat exposed wall, for a connection of this kind will permit comparatively free expansion and contraction of the central portions which are subjected to relatively high temperatures. The invention, however, lies in certain combinations of elements which will be particularly pointed out in the claims, it being understood that the invention comprehends modifications and equivalents of the structure herein shown.

The combustion chamber formed by the recess R is elongated, and a question may arise as to whether the combustion in an elongated chamber will be as complete or perfect as the combustion in a circular chamber. Complete combustion in a Diesel engine depends primarily upon whether the fuel is sprayed into the combustion chamber, so as to thoroughly penetrate the entire body of air therein. I therefore believe it is desirable to use a piston having an approximately convex top face onto which the fuel is sprayed as shown in Fig. III. This fuel-receiving face is inclined downwardly from the center of the piston, and the fuel striking the inclined face will be deflected and distributed in the elongated chamber R, as suggested by Fig. III. Furthermore, the substantially convex piston top is comparatively strong, and it reduces the height at the center of the combustion chamber. Inasmuch as the center of the cylinder head is usually overheated, there is some advantage gained by reducing the volume of burning fuel at the center of the combustion chamber.

Fig. V illustrates a modification wherein an inlet port 9^a for the injection of fuel is formed in one side of the cylinder head, instead of in the top wall 10.

I claim:

1. An internal combustion engine provided with a cylinder head having marginal portions, an elongated expanding central portion exposed to the heat resulting from combustion in the engine, said heat-exposed elongated central portion being offset relative to said marginal portions, and a yieldable connection integrally connecting said central and marginal portions to permit differential expansion thereof.

2. An internal combustion engine provided with a cylinder head having marginal

portions, an elongated expanding central portion exposed to the heat resulting from combustion in the engine, said elongated expanding central portion being offset relative to said marginal portions to form the top wall of an elongated recess in the heat-exposed face of said head, and a yieldable connection integrally connecting said central and marginal portions to permit differential expansion thereof, said yieldable connection forming the side walls of said recess.

3. An internal combustion engine provided with a cylinder head having marginal portions, an elongated expanding central portion exposed to the heat resulting from combustion in the engine, said elongated expanding central portion being offset relative to said marginal portions to form the top wall of an elongated recess in the heat-exposed face of said head, and a yieldable connection integrally connecting said central and marginal portions to permit differential expansion thereof, said yieldable connection forming the side walls of said recess, and the elongated top wall of said recess being provided with an inlet for the admission of combustion fluid and also with an air inlet port and an exhaust port.

4. An internal combustion engine provided with a cylinder having a seat at its upper end, a hollow cylinder head through which cooling fluid is transmitted, fastening devices whereby said head is detachably secured to the cylinder, said cylinder head having marginal portions contacting with said seat, an elongated expanding central portion exposed directly to the heat resulting from combustion in the engine and also to said cooling fluid, said elongated expanding central portion being offset relative to said marginal portions to form the elongated top wall of an elongated recess in the heat-exposed face of said head, and a relatively narrow yieldable connection integrally connecting said central and marginal portions to permit differential expansion thereof, said yieldable connection forming the side walls of said recess, and the elongated heat-exposed top wall of said recess being provided with an inlet for the admission of combusti-

ble fluid and also with an air inlet port and an exhaust port.

5. An internal combustion engine provided with a cylinder head having marginal portions, an elongated expanding central portion exposed to the heat resulting from combustion in the engine, said elongated expanding central portion being offset relative to said marginal portions to form the top wall of an elongated recess in the heat-exposed face of said head, and a yieldable connection integrally connecting said central and marginal portions to permit differential expansion thereof, said yieldable connection forming the side walls of said recess, said recess being elongated transversely of the cylinder to provide an elongated combustion chamber in said cylinder head, a piston facing said elongated top wall, and a fuel injector whereby fuel is injected away from said top wall and onto said piston, the fuel-receiving face of said piston being inclined downwardly from its center to provide for the distribution of fuel in the elongated combustion chamber formed by said recess.

6. An internal combustion engine provided with a cylinder head having marginal portions, an expanding central portion exposed to the heat resulting from combustion in the engine, said elongated expanding central portion being offset relative to said marginal portions to form the top wall of a recess in the heat-exposed face of said head, and a yieldable connection integrally connecting said central and marginal portions to permit differential expansion thereof, said yieldable connection forming the side walls of said recess, said recess providing a combustion chamber in said cylinder head, a piston facing said top wall, and a fuel injector whereby fuel is injected into said recess and onto said piston, the fuel receiving face of said piston being inclined downwardly from its center to provide for the distribution of fuel in the combustion chamber formed by said recess.

In testimony that I claim the foregoing I hereunto affix my signature.

REINHARD HILDEBRAND.
